UNITED STATES PATENT OFFICE.

THOMAS S. HANEY, OF GRANDVIEW, WEST VIRGINIA.

TOY ENGINE.

Application filed June 13, 1928. Serial No. 285,112.

This invention relates to an electric motor simulating a steam engine.

An object of the invention is the provision of a device exhibiting the characteristics of a steam engine while being electrically driven, the boiler in this instance operating as a housing for either an electric battery or a transformer, with wires running along the exterior of the boiler in such a manner as to simulate steam pipes.

A further object of the invention is the provision of an electric motor simulating a steam engine in which a movable core operating as a piston is controlled in its reciprocating movement by a coil periodically energized through a switch which is operated by a cam on the crank shaft, a relatively fixed core being included in the solenoid being adjustable lengthwise of the core and cooperating with the said coil for causing the piston to be drawn into the coil, and causing rotation of the crank shaft through a pitman and crank.

This invention will be best understood from a consideration of the following detailed description, in connection with the accompanying drawings; nevertheless, it is to be understood that the invention is not confined to the disclosure, being susceptible of such changes and modifications as shall define no material departure from the salient features of the invention as expressed in the appended claims.

In the drawings:—

Figure 1 is a side view in elevation of an electrically driven engine,

Figure 2 is a transverse vertical section of said engine,

Figure 3 is a plan view of the engine constructed according to the principles of my invention,

Figure 4 shows more or less diagrammatically a circuit which includes a solenoid.

Referring more particularly to the drawings, 10 designates a base member formed of relatively stiff sheet metal and pressed to shape. A housing 11 in the shape of a boiler of a locomotive is mounted on the base member 10 and is provided with a smoke stack 12, and a steam dome 13, and a fire box 14.

The boiler is hollow, as shown in Fig. 3, and provides a chamber which is of sufficient capacity to receive a storage battery 15 which runs longitudinally of the boiler having the ends provided with contacts 16 and 17 projecting into the fire box 14.

The contacts 16 and 17 have respectively

secured thereto wires 18 and 19. Wire 19 passes through one side of the boiler 11, then upwardly through the steam dome 13 and out through the top of the same, and into a switch box 20. A wire 21 extends from the switch box across one side of the boiler and then downwardly and through an opening in the base member 10. The wire, as shown in Fig. 3, is extended beneath the under face of the base and is passed through a perforation 22 in the base member and connected with a switch element 23, of a switch 24. The wire 18 is carried through a passage in the base member, then downwardly beneath its under face and upwardly through an opening in the base member and connected with one end of a coil 25. The other end of the coil is grounded at 26.

Having now described the circuit, it will be seen that the coil 25 is included in one of the elements of the solenoid which is wound upon a brass tube or cylinder 30 and inclosed by a casing 31 formed of insulating material and simulating a steam cylinder of an engine. The cylinder 30 may be formed of any non-magnetic material which will not be affected by the lines of force from the coil 25. This cylinder is provided with flanges 32 at its outer ends which are secured to the end walls 33 of the housing 31. A core 34 in the form of a piston is slidably mounted in the brass tube 30 and is adapted to operate a pitman 35 rigidly connected with the cylinder. A relatively fixed core 36 in the form of a screw is threaded into a boss 37 in the end member 33. A spring coil 38 having one end in engagement with the boss 37 and its other end in engagement with a finger piece 39 which tends to place the screw in rigid contact with the threads in the boss 37 for maintaining the screw in position when once adjusted. The screw has approximately the same cross sectional area as the piston 34. The coil 25 is formed of a pair of wires connected together and of such suitable dimensions as to cause the core 34 to be drawn into the cylinder 30 when the coil is energized. A crank shaft 40 is mounted in bearings 41 formed at the upper end with standards 42 and has a crank 43 secured at 44 to the pitman or connecting rod 35. A pair of flywheels 45 are rigidly connected to the crank shaft 40 upon opposite sides of the crank 43.

A pair of guide rods 50 are secured to the end wall 33 of the housing 31, and also to a bracket 51. A cross head 51 secured to the

outer end of the piston 34 is provided with passages to receive the guides 50.

A casing 55 simulating a steam chest is secured to the cylinder or housing 31 and a rod 56 which represents a valve rod is received within the steam chest 55 and has an eccentric ring 57 mounted on an eccentric 58 of the shaft 40, so that when said shaft is revolved, the rod 56 will be reciprocated 10 and moved in and out of the steam chest 55.

The switch 24 consists of a fixed switch member 23 having a contact 60 adapted to be engaged by a contact 61 of a movable switch element 62 hinged at 63 to the base member 10. A spring member 64 is rigidly connected with the movable switch element 62 and is in normal engagement with a cam member 65 rigid with the crank shaft 40. The movable arm 62 of the switch 24 is connected by means of a wire 66 to a ground 67. The ground in this case forms the base member 10. A pitman 35 is connected at 70 with a link 71 of the crank 43.

A door 75 is hingedly mounted at 76 to one edge of the fire box 14 and is provided with a latch 77 adapted to engage a keeper 78 for securing the door in position. A handle 79 is secured to the latch 77 for operating the same. A U-shaped member 80 is secured 30 to the door 75 providing the keeper on the outer face of the door.

It will be noted that the housing 31 is mounted on a base member 81, which in turn is mounted on a second base member 82 secured to the base 10. The housing 31 is mounted at such an angle that the angle of the cylinder 30 will be inclined at a slight acute angle to the horizontal, so that the piston 34 when moved through the cylinder 30 will engage but a small portion of the cylinder to prevent excessive wear on the cylinder. The bracket 51 is secured to the auxiliary base member 82 and extends upwardly in a vertical plane and is bifurcated at 83 to receive the pitman 35.

The operation of my device is as follows:

A switch 20 is operated to close the circuit to the solenoid including the coil 25. It may be necessary to manually rotate the fly wheels 50 45, but after this is done the momentum of the fly wheels will be sufficient to withdraw the piston 34 from the brass cylinder 30 when the contacts 60 and 61 have been separated and when the free ends of the spring 64 is 55 engaged in the reduced portion of the cam member 65. When the fly wheels have been revolved sufficiently the cam 65 will act on the spring arm 64 and force the contact 61 into engagement with the contact 60, thereby 60 closing the circuit to the coil 25 which when energized will cause the piston 34 to be moved

into the cylinder 30 and through the link 71 and crank 43 continue the rotation of the fly wheels. The cam member 65 is so constructed that it will maintain the circuit closed for approximately one-third of the revolution of a fly wheel.

The core 36 coming through the lines of force at one end of the coil and being formed of soft iron will be temporarily magnetized and act to aid in drawing the piston 34 into the cylinder 30 and thereby increase the power for actuating the piston 34. The threaded core 36 is adjustable in the cylinder 30 and can be adjusted by the rotation of the finger piece 39 against the tension of the spring 38. This core should be adjusted so that it will not touch the free end of the piston when the same has been moved to its limit of stroke in the cylinder. The adjustment should be 80 such that the greatest amount of power will be exerted on the piston 34, and this can be determined by inspection of the operation of the engine.

The coil 25 consists of a pair of wires in series and of such diameters that they will operate the piston 34 with the least amount of current. It will be seen that the construction presents in its entirety the appearance of a steam engine while being operated by electric current and, therefore, eliminates the danger of the use of steam by minors who are not capable of understanding the dangers.

I claim:—

1. An electric motor simulating a steam engine and comprising a housing in the shape of a boiler, a battery in the housing, a solenoid including a coil and a piston movable in the coil, a circuit including the battery and coil, a crank shaft, a fly wheel rigid with the shaft, means connecting the piston with the crank shaft for causing rotation of the shaft when the solenoid is energized, and means for causing the battery to energize the solenoid intermittently, an adjustable core cutting the lines of force of the solenoid.

2. An electric motor simulating a steam engine and comprising a housing in the shape of a boiler, a battery in the housing, a solenoid including a coil and a piston movable in the coil, a circuit including the battery and coil, a crank shaft, a fly wheel rigid with the shaft, means connecting the piston with the crank shaft for causing rotation of the shaft when the solenoid is energized, means for causing the battery to energize the solenoid intermittently, a core having a relatively fixed position within the coil, and being adjustably mounted so that the core may be moved towards or away from the free end of the piston.

THOMAS S. HANEY.
